CLAIM

The ornamental design for an auxiliary handle grip, as shown and described.

DESCRIPTION

FIG. 1 is a perspective view of an auxiliary handle grip showing our new design;

FIG. 2 is a side view thereof, the opposite side view being the same;

FIG. 3 is a top view thereof;

FIG. 4 is a bottom view thereof; and,

FIG. 5 is an end view thereof, the opposite end view being the same.

The broken lines in FIGS. 1 and 5 and showing a wire bail and handle are for illustrative purpose only and form no part of the claimed design.
